(57) **CLAIM**

The ornamental design for a skate blade, as shown and described.

DESCRIPTION

FIG. 1 is perspective view of a skate blade according to my new design;

FIG. 2 is a top plan view thereof;

FIG. 3 is a bottom plan view thereof;

FIG. 4 is a first side elevation view thereof, the opposite side elevation view being a mirror image thereof;

FIG. 5 is a front elevation view thereof; and,

FIG. 6 is a rear elevation view thereof.

The broken lines showing is included for the purpose of illustrating portions of the skate blade that do not form part of the claimed design.

1 Claim, 3 Drawing Sheets
